ATTORNEY

UNITED STATES PATENT OFFICE

JOHN B. ELLIS, OF SAN JOSE, CALIFORNIA

SHADE

Application filed April 22, 1929. Serial No. 357,192.

This invention relates particularly to a vertically hanging porch shade.

It is the object of the invention to provide a shade of the character indicated that is so constructed as to insulate the inner surface of the shade against the heat naturally stored therein by the action of the sun's rays upon its outer surface, thereby preventing transfer of heat to the interior of the porch protected by the shade by conduction.

In the drawing, the figure is a perspective view of a portion of a shade constructed in accordance with my invention.

Shades of the type indicated are built up of a number of identical slats as indicated at 1-1, the slats being fastened together to hang in a vertical plane and in parallel relation to each other by means of suitable cords as at 2. This construction also permits them to be rolled into a small compact bundle when not in use.

In carrying out my invention I form, in any suitable manner, a plurality of parallel conduits or passages as 3 in each slat and extending therethrough to communicate with its upper and lower edges as clearly shown in the drawing.

When a shade is constructed in this manner and properly hung to shade a porch or room from the sun's rays, the outer surface of the several slats becomes heated and the heat penetrates the slats to the passages 3. Since by this means the air in the several passages is heated a circulation of air is set up therethrough, cool air entering the several passages at the bottom and discharging at a higher temperature at the top, thereby preventing the heat from reaching the inner surface of the slats and so heating the air to the rear thereof.

The desired result may be obtained more perfectly if the passages are inclined from the lower inner edge as at 4 to the outer and upper edge as at 5, the other two edges of the slat being bevelled as indicated at 6 and 7 respectively.

It is to be understood, of course, that while I have herein shown and described but one specific embodiment of the invention, changes in form, construction and method of assem-

bly and operation may be made within the scope of the appended claims.

I claim:

1. A shade element comprising a slat having a plurality of open and unobstructed passages formed therein and passing therethrough from edge to edge thereof whereby to permit the free circulation of air therethrough. 55

2. A shade element comprising a slat having a plurality of open and unobstructed juxtaposed passages formed therein and passing therethrough from edge to edge thereof whereby air may circulate freely through the slat from edge to edge thereof. 60 65

3. A shade of the character described comprising a plurality of slats mounted to hang in a common plane and in spaced relation to each other, each slat having a plurality of open and unobstructed juxtaposed 70 passages formed therein and passing therethrough whereby air may circulate freely through the slat from edge to edge thereof.

JOHN B. ELLIS.
